FUEL INJECTION APPARATUS FOR INTERNAL COMBUSTION ENGINES

Juri Puurmann, Paris, France

Application October 28, 1935, Serial No. 47,171
In France October 31, 1934

5 Claims. (Cl. 74—53)

This invention has for its object improvements in and relating to fuel injecting pumps permitting the use of pistons and cylinders having no asymmetrical slots, whereby irregular wear is done away with; a precise control of the stroke of the pump piston as well as the lubrication of the said organs with oil; and also permitting thereby the use of a light fuel having no inherent lubricating properties.

10 In the appended drawing there is shown, by way of example, a piston injecting pump with device for adjusting the stroke of the pump.

In the said drawing
Figure 1 is a cross sectional view of the pump.
15 Fig. 2 is a cross-sectional view of the device for adjusting the stroke of the pump piston.
Fig. 3 is a plan view of the adjusting device.
Fig. 4 is a profile view of the actuating lever.
Fig. 5 is a plan view of the lever of Fig. 4.

20 Fig. 6 is a view of the lateral adjusting lever of the link.
Fig. 7 is a plan view of the lateral lever of Fig. 6.
25 13 is the pump piston, 14 the cylinder, 15 the return spring, 16 the fuel inlet, 17 the suction valve, 18 the discharge valve, 19 the discharge passage, 20 the lubricating oil inlet, 21 the circular oil passage, 22 the oil hole in the cylinder, 23 are the circular oil grooves in the piston, 24 is the non-return valve body and 25 the non-return valve for the lubricating oil.

The pump comprises one or more cylinders 14. The piston receives a reciprocating movement from a cam 3 by means of the levers 5—6, a 35 pusher 12, and the return spring 15.

The adjusting device comprises two levers 5 and 6. The first lever 6 is secured to the pump body at one of its ends by means of a stud 7. Its other end is also provided with a pin 4a carrying a roller 4 following the cam 3 of the pump.

To this pin 4a is secured the second lever 5, the second end of which remains free. This second lever 5 is located between the bearing point of the pusher of the piston rod 13 (or of the piston 13 in the case when there is no pusher) and a ledge (10 or 26) which is movable and serves as a variable fulcrum. This fulcrum (10 or 26) is adjustable along the second lever 5 and rests on the pump body; thus it serves to change the amplitudes of oscillation of this lever 5 and also to vary the stroke of the piston 13 between 0 and its maximum.

During rotation the cam 3 works, by means of the roller 4 and of the lever 5, on the pusher 12, 55 which raises the piston 13 of the pump. An end

of the lever 6 is secured to the stud 7 on which it freely turns. The middle line of this stud is fast with respect to the pump body. On the said stud or on another suitable axis can be also fixed the cranks 8 which are connected, by means 5 of links 9, with the ledge 10 serving as a variable fulcrum. On the stud 7 is also fixed the lever 11 (Figure 3) which is connected with the governor of the engine or with the gas pedal. When the stud 7 is turned it changes the position of the variable fulcrum 10 by means of the crank 8 and of the links 9, the axis being brought farther from or nearer to the axis of the pump piston.

When the fulcrum axis lies in the middle line of the pump piston, as shown in Figure 1, the lever 5 being raised by the cam 3 by means of the roller 4, the said lever only rocks about the variable fulcrum 10 and raises neither the pusher 12 nor the pump piston 13.

As the fulcrum 10 moves farther from the middle line of the piston, the lever 5 begins to rise and to raise the piston 13 of the pump. When the fulcrum reaches its utmost position, as shown in Figure 2, the stroke of the pump piston reaches its maximum. This stroke is 25 shown in broken lines in Figure 2.

Thus, it is possible to adjust the stroke of the pump piston with precision by turning the stud 7 through which the variable fulcrum 10 on which the lever 5 rests is brought nearer to or farther 30 from the middle line of the pump piston. This device causes no resistance at the governor, since friction is reduced to a minimum.

By controlling the fuel discharge through a variation of the piston stroke, a very short stroke 35 is obtained for the pump piston, thus permitting the pump to rotate at a very great velocity.

Another feature of the invention relates to the lubrication of the piston and the cylinder. With an oil lubrication under pressure or without pressure for the cylinders and the pistons a more complete tightness is obtained for the pump and the said cylinders and pistons are protected against wear. The pressure of the lubricating oil can be selected greater than the pressure of the 45 fuel. When the pressure of the lubricating oil is greater than the pressure of the fuel, the utmost security for the tightness of the pump is obtained. Under normal conditions it is possible to work with a low pressure for the lubricating oil or even 50 at atmospheric pressure. A particular device for lubrication under pressure is described in my divisional application.

The lubricating oil is introduced through a double coupling 24 (Figure 1) provided with a 55

non-return valve 25. The oil which fills the circular lubrication passages absolutely opposes a flow of fuel and simultaneously lubricates the pistons and cylinders of the pump.

5 Of course, the invention, which has been described as applied to a fuel injecting pump, can be also applied to all kinds of pumps for any liquid or even for gases.

10 The invention is also applicable to the various valves for explosion engines, Diesel engines, turbines and other prime movers or movable pieces. The above described device for varying the piston stroke can be used also for varying the stroke of the valves of any engine cylinders by adjusting the same in relation with the other characteristics of the engines, such as suction, scavenging, exhaust and the like.

15 In a like manner, the adjusting device for adjusting the piston stroke can be used also for adjusting the stroke of other members such as, for instance, valves or moving mechanical pieces actuated by the rotation of a cam.

20 Lastly it is also possible, of course, without departing from the spirit of the invention, to add 25 to the above described fundamental device various auxiliary levers or springs adapted to facilitate the operation of the same.

I claim:

1. A variable stroke mechanism comprising a 30 rotary cam, a lever rocked by said cam, a driven member freely bearing on one side of said lever at the middle thereof, a fulcrum member bearing on the opposite side of said lever and adjustable rectilinearly along the lever between the middle 35 thereof and the end remote from the cam, and a second lever pivoted about a fixed axis and jointedly connected to the first-mentioned lever.

2. A mechanism according to claim 1, in which the joint connection between the two levers carries 40 means driven by the cam.

3. A variable stroke mechanism comprising a rotary cam, a lever rocked by said cam, a driven

member freely bearing on one side of said lever at the middle thereof, a fulcrum member bearing on the opposite side of said lever and adjustable along the lever between the middle thereof and the end remote from the cam, a second lever pivoted about a fixed axis and jointedly connected to the first-mentioned lever, and means for guiding the fulcrum member in a rectilinear path. 5

4. A variable stroke mechanism comprising a rotary cam, a lever rocked by said cam, a driven member freely bearing on one side of said lever at the middle thereof, a fulcrum member bearing on the opposite side of said lever and adjustable rectilinearly along the lever between the middle thereof and the end remote from the cam, and a second lever pivoted about a fixed axis and jointedly connected to the first-mentioned lever, said second lever being forked with the first-mentioned lever jointedly supported at one end between the arms of the fork, the other end of the first-mentioned lever resting freely on the fulcrum member. 10

5. A variable stroke mechanism comprising a rotary cam, a lever rocked by said cam, a driven member freely bearing on one side of said lever at the middle thereof, a fulcrum member bearing on the opposite side of said lever and adjustable rectilinearly along the lever between the middle thereof and the end remote from the cam, a second lever pivoted about a fixed axis and jointedly connected to the first-mentioned lever, said second lever being forked with the first-mentioned lever jointedly supported at one end between the arms of the fork, the other end of the first-mentioned lever resting freely on the fulcrum member, a shaft constituting the fixed axis of said second lever, said shaft being parallel to the axis of rotation of the cam, an arm on said shaft, a link connection between said arm and the movable fulcrum member, and means for 20 turning the shaft to adjust said member. 25
